UNITED STATES PATENT OFFICE.

EDWIN J. BERIAULT, OF NEW ORLEANS, LOUISIANA.

HINGE.

1,030,801.

Specification of Letters Patent. Patented June 25, 1912.

Application filed February 27, 1912. Serial No. 680,330.

To all whom it may concern:

Be it known that I, EDWIN JAMES BERIAULT, a citizen of the United States of America, residing at New Orleans, in the 5 parish of Orleans and State of Louisiana, have invented certain new and useful Improvements in Hinges, of which the following is a specification.

The object of my invention is to provide 10 a new and improved loose pin butt or hinge which may be used in either right or left position and in which the pin, while loose and removable in some positions of the leaves of the hinge, will be held securely in 15 all other positions of the leaves.

In the accompanying drawings which 20 show the preferred forms of my invention: Figure 1 is a perspective view of the assembled butt or hinge. Fig. 2 shows a plan of 25 the butt as attached. Fig. 3 is an enlarged end view with the outer portions of the leaves broken away. Fig. 4 is a side view 30 of a section on the line 4—4 of Fig. 3. Fig. 5 is a view in perspective of the separated leaves and the pin partially extracted. Fig. 35 6 is a view similar to Fig. 5 but showing a modified construction.

For convenience of description the two leaves of the hinge as shown in the drawings 40 will be referred to as right and left leaves respectively, but it will be readily understood that when used in the reversed position the terms right and left are interchanged.

The hinge comprises the two leaf members 45 1 and 2 of wrought iron, mild steel or other metal, each member being provided with spaced eyes or knuckles 3 and 4 formed in the usual manner from straps cut in the leaf blank. As shown, the left hand leaf member has three knuckles spaced apart to receive 50 between them the two knuckles 4 of the right hand member 2. When assembling the knuckles are brought into alinement and a metal pin 5 is inserted.

So far the construction of the butt or hinge is common and is known as the ordinary loose pin butt or hinge. This form of hinge was found objectionable, however, as 55 the pin could be readily driven out or re-

moved and the door or window blind could be easily opened, and the object of my invention is to provide a construction whereby the pin will be securely locked in all positions of the hinge except that particular 55 one in which the pin may be readily removed. To this end the pin 5 is provided with a lug or projection 6 which may be formed integral with the pin or may be made by driving a piece of metal into a recess formed in the pin. This lug or projection 6 is located on the pin in position to fit in a recess or seat 7 formed in the outer end of the top knuckle 4 of the right leaf 2, and the end knuckle 3 of the left leaf is provided 60 with a groove 8 cut in its inner wall which permits the passage of the lug, and when assembled with the lug 6 received into the seat 7 the pin is securely held, as the inner end of the knuckle 3 closes the open 65 end of the seat 7. Preferably the seat 7 and the groove 8 are located in their respective knuckles so that they are only in alinement when the two leaves are in a position at a right angle to each other. 70

Instead of grooving the end knuckle as shown in Figs. 1 to 5, the passage for the lug may be formed by cutting the strap for the end knuckle slightly short, so that the strap when bent to form the knuckle will 75 80 not entirely close and a slot or passage 8 as shown in Fig. 6 will be left between the end of the strap and the leaf.

If desired the head of the pin may have marked thereon an arrow or other indicator 85 to indicate the position of the lug so that in order to remove the pin it is only necessary to bring the slot or groove in the knuckle in alinement with the indicator. When the groove is formed wholly interiorly 90 of the knuckle, as in Fig. 5, an indicator mark may be also made on the exterior of the knuckle to show the position of the groove.

The recess or seat 7 in the knuckle 4 may be 95 a notch or a slot or passage cut through the entire vertical length of the knuckle, the object being to provide any suitable aperture into which the lug or projection 6 will fit. Should it be deemed desirable to use wash- 100

ers of metal, fiber or any material between the respective knuckles, these washers may be cut to allow the passage of the lug 6.

Having thus described my invention I 5 claim:

A loose pin butt or hinge comprising a plurality of leaves each leaf having a knuckle, and a pin engaging in said knuckles, said pin being provided with a lug or pro- 10 jection and one of said knuckles having a

seat to receive said lug and hold the pin from turning while the other knuckle is arranged to permit the passage therethrough of said lug.

In testimony whereof I affix my signature 15 in presence of two witnesses.

EDWIN J. BERIAULT.
